United States Patent Office

Des. 208,141
Patented July 18, 1967

208,141

CAN OPENER

Sigvard Bernadotte, Villagatan, Sweden, assignor to AB
Nilsjohan, Stockholm, Sweden, a corporation of
Sweden

Filed Mar. 25, 1966, Ser. No. 1,645

Term of patent 7 years

(Cl. D95—2)

FIGURE 1 is a perspective view of a can opener showing my new design;

FIGURE 2 is a side elevational view of the can opener of FIGURE 1 as viewed from the right hand side;

FIGURE 3 is a side elevational view of the can opener of FIGURE 1 as viewed from the left hand side;

FIGURE 4 is a top plan view of the can opener of FIGURE 1;

FIGURE 5 is a bottom view of the can opener of FIGURE 1, and

FIG. 6 is a rear elevational view thereof.

The dominant features of the design reside in the full line portions of the drawing.

I claim:

The ornamental design for a can opener, substantially as shown and described.
